UNITED STATES PATENT OFFICE.

MAX LICHT AND LEONARD D. LICHT, OF KNOXVILLE, TENNESSEE.

DESIGN FOR A BOTTLE.

Application filed November 15, 1927. Serial No. 24,138. Term of patent 14 years.

To all whom it may concern:

Be it known that we, MAX LICHT and LEONARD D. LICHT, citizens of the United States, residing at Knoxville, in the county of Knox and State of Tennessee, have invented a new, original, and ornamental Design for Bottles, of which the following is a specification, reference being had to the accompanying drawing, forming part thereof.

The figure is an elevational view of a bottle, showing our new design.

We claim:

The ornamental design for a bottle, as shown.

MAX LICHT.
LEONARD D. LICHT.
